UNITED STATES PATENT OFFICE.

FRANK SPILL, OF EAST RUTHERFORD, NEW JERSEY, ASSIGNOR TO THE SIESEL-SPILL
MANUFACTURING CO., INC., OF NEW YORK, N. Y.

DESIGN FOR A SPANISH COMB.

Application filed March 17, 1923. Serial No. 5,498. Term of patent 3½ years.

To all whom it may concern:

Be it known that I, FRANK SPILL, a citizen of the United States of America, and a resident of East Rutherford, in the county of Bergen and State of New Jersey, whose post-office address is 104 Cornelia Street, in said city, have invented a new, original, and ornamental Design for a Spanish Comb for Ladies' Hair and Head Ornament, of which the following is a specification, reference being had to the accompanying drawing, forming a part thereof.

I claim:

The ornamental design for a Spanish comb as shown and described.

FRANK SPILL.
